Fig. 4

Fig. 6

FIG. 1 is a perspective view of the catalytic heater showing my new design;

FIG. 2 is a top view of the catalytic heater on a reduced scale thereof;

FIG. 3 is a side elevational view thereof;

FIG. 4 is an end elevational view;

FIG. 5 is a bottom plan view; and

FIG. 6 is an end elevational view with the wings in the folded position.

Suspension cables are shown in broken lines in FIGS. 1 and 4 for illustrative purposes only.

I claim:

The ornamental design for a catalytic heater, as shown and described.
